(57) **CLAIM**

The ornamental design for a box blank, as shown and described.

DESCRIPTION

FIG. 1 is an outside plan view of a box blank showing our new design; and,

FIG. 2 is an inside plan view thereof.

The broken lines in FIGS. 1 and 2 represent crease lines on the flat surface designed to accommodate folding during box assembly.

1 Claim, 2 Drawing Sheets

FIG. 1

FIG. 2
